HELMET

Gustav Illguth, Langwaltersdorf, Germany

Application July 7, 1936, Serial No. 89,354
In Germany August 8, 1935

3 Claims. (Cl. 2—6)

This invention relates to an improved construction of helmets, especially for motor vehicle drivers, and enables the wearer to clearly hear sounds on the road and in the neighbourhood.

The commonly used helmets are constructed so that they cover also the ears of the wearer. These known helmets damp the sounds to such an extent that the wearer is often unable to hear clearly the approach of a vehicle overtaking him and even hooter signals, especially when he is riding a motor cycle or driving in an open car when the sound of wind caused by travelling is often very loud. The result is, that the wearer of the known helmets does not feel safe, especially on roads with heavy traffic, and therefore is uncertain in the steering of his vehicle.

It has already been proposed to provide a head gear with flexible flaps covering apertures opposite the wearer's ears. Such flaps are rolled up and expose the apertures when the wearer desires to hear readily and they are extended to overlie the apertures to prevent wind entering the apertures.

In this device the apertures are either protected against the wind and the wearer cannot hear, or they are exposed and the wind can freely enter the apertures.

It has also been proposed in ear protectors to provide shield members which are held in open position by the wearer's external ears projecting from apertures in the protectors. This has that drawback, that the external ears get chilled by the direct contact with the shields, and are subjected to chafing by friction against the inner side of the shields.

The helmet according to the invention constitutes an improvement over the known constructions in that stiff wind screen walls constructed as sound reflecting surfaces are hingedly connected to the helmet one in front of each ear aperture with the result that a maximum audibility is obtained especially as regards sound waves coming from behind the wearer. Means such as flexible straps are provided for rigidly holding the walls either in open position and away from the wearer's ears, or in folded or closed position, as desired.

The fundamental idea of the following experiments has been utilized:—When a passenger riding on a motor cycle places both hands in front of his ears in half shell-shape open towards the rear, the disturbing wind noise on the ear apertures ceases and the sound of vehicles approaching from the rear or coming round a corner can be heard much earlier and more distinctly.

The improvement in the audibility when thus holding the hands, is due to two reasons, firstly to the displacement and removal of the head wind from the ear apertures and secondly to the reflection action of the palms of the hands forming sound chambers which catch the sound waves coming from the rear and amplify and reflect them on to the ear in the direction which corresponds to the natural position of the ear shell.

Owing to their wind deflecting property, the protecting walls do not even affect the audibility for sounds coming from in front when travelling, so that a vehicle approaching from in front can under certain circumstances be heard sooner and more distinctly.

The known experiments for providing a driver's helmet with devices which do not affect the sense of hearing solve the problem of protecting the ear against the mechanical and thermic irritations caused by direct exposure to the head wind and thereby maintain audibility when the vehicle is stationary. When for this purpose ear flaps or the like projecting from the helmet are employed, these are either too small or are made of too yielding or too permeable material to be suitable under the stress of the strong head wind or to obtain the above described acoustic effect and thereby an improvement in the sense of hearing. In the case of too small protecting devices the head wind brushes past the hearing aperture in much too close proximity thereto so that an appreciable relief from the head wind noise is not obtained, and moreover, too small protecting devices do not offer a catching or refractory resistance to the sound waves coming from the rear, so that the greater part of the sound waves coming from the rear must brush past the ear without being caught. In the case of insufficiently rigid protecting devices, they collapse or flatten under strong head wind and are pressed against the ears so that they have the same disadvantages as regards the head wind and sound waves coming from the rear.

As compared with all these constructions, the invention according to the experiment above mentioned presents the great advantage in the production of a helmet which deflects the head wind far around and over the ears somewhat like a snow plough, completely shelters the ears and thus excludes to a maximum extent the superimposition of sound waves caused by the head wind on the ear apertures, and which also catch the sound waves emanating from the rear and even amplify and reflect them on to the ear. This problem is solved according to the invention by

the arrangement of large rigid or stiffened protecting walls or protecting chambers open at the rear, which are arranged in front of the apertures situated in the range of the ears and which, 5 as regards position and material, are capable of offering sufficient resistance to the stresses of the head wind or are held in position by suitable means. In dimensioning these ear protecting arrangements, the acoustic laws must be taken into 10 consideration as far as the practical manipulations will allow, namely that the disturbance caused by the head wind is reduced in a ratio of the square to the distance of the head wind from the ear aperture.

15 As the protecting walls effectively protect the ear shells at the front from mechanical and thermic irritations caused by the head wind, the ears may be exposed and project through sufficiently large apertures in the material of the helmet. At the same time another acoustic advantage is obtained, besides the mechanical relief which in time is found to be very soothing and agreeable, i. e. owing to the baffles or protecting walls arranged in front of the ears the sound waves coming from the rear are reflected in the 20 direction of the natural position of the ear shells so that these can secure their sound energies from the direction which corresponds to the natural position. Moreover, the sound receiving and 25 amplifying effect of the whole ear shell is utilized for hearing and not only the hearing aperture as hitherto usual with the known helmets.

The protecting walls are hingedly connected to the helmet so that they can be employed for closing the ear apertures in the helmet and held 30 in open position by straps or other means.

An embodiment of the invention is illustrated by way of example in the accompanying drawing, in which:—

40 Fig. 1 shows the helmet in front elevation in position for use.

Fig. 2 is a side elevation of Fig. 1.

Fig. 3 is a top plan view of Fig. 1.

45 Fig. 4 shows on a larger scale a perspective view of the protecting wall arrangement.

The protecting walls or flaps *a* are arranged on the head in front of the ears and at an angle of about 60° relative to the head.

Between the upper and lower edges of the walls *a* and the helmet *c* or the like intermediate parts *e* of pliable or foldable material, such as leather, 50 are provided which border the space between the protecting walls and the ears at the top and bottom and thus prevent the penetration of rain, gusts of wind and the like into this space. The 55 protecting walls *a* are held in open position by means of straps *f*. Press buttons *g* may be provided on the walls or on the helmet for fixing

these straps. A button *k* is located to the rear of each flap *a*. When it is desired to close the apertures *g*, the upper ends of the straps *f* are detached from the press buttons *g*, the walls *a* are folded against the sides of the helmet, and the upper end of each strap is connected to the corresponding button *k*. The walls may also be held in the lateral position by fixable hinges, steel band springs or the like. The protecting walls *a* have a stiff or stiffened shape which is attained for example by the provision of a frame of metal, celluloid or other suitable material. The hinged fixation of the protecting walls on the helmet can be carried out in any desired manner.

15 The protecting walls *a* may be made of leather or other material for example arranged in layers connected by stitching *h* or other suitable means. Moreover, they may be of any suitable shape which causes the protecting walls, when in closed 20 position, to bear tightly against the ears. By providing elastic insertions only at the edge any disagreeable pressure can be avoided. The protecting chambers open at the rear may be formed so that they extend over the ears in half-shell 25 or similar shape.

It is evident that band frames, head straps or other suitable means, including caps and other head wear, can serve as supports for the protecting wall.

30 Holes or slots may also be provided in the protecting walls for the goggle straps, or the protecting walls may be made of such shape or so arranged that the goggle straps can lie above the upper edge of the walls.

35 In Fig. 3 the deflection of the air flow is indicated by the lines *x*.

I claim:—

1. A helmet especially for motor vehicle drivers, comprising in combination a helmet shaped body, 40 having apertures at the ear portions, stiff wind screen walls constructed as sound reflecting surfaces hingedly connected to said helmet one in front of each of said apertures, and means for rigidly holding said walls either in open projecting position spaced away from the external ears of the wearer, each wall forming with said helmet an angle open towards the rear, or folded in closed position.

2. A helmet as specified in claim 1, in which the apertures in the helmet are sufficiently large 50 to allow the passage of the whole external ears.

3. A helmet as specified in claim 1 in which the means for holding the walls in open and closed position are detachable, flexible straps attached to the front sides of the walls.

55 GUSTAV ILLGUTH.
